WEIGHT SUPPORTING MECHANISM

Robert A. Forbes, 515 Harrison St., Monroe, Mich.

Filed July 15, 1957, Ser. No. 671,818

10 Claims. (Cl. 187—1)

This invention relates to devices for lifting, supporting, transporting and lowering objects and more particularly to devices of this type having sliding supports or anchoring devices therefor.

An object of this invention is to provide means for lifting, supporting, and lowering heavy, elongate objects, such as metal bars, or the like.

Another object of this invention is to provide means of the above character having a pair of spaced fulcrum-forming means, each of which alternately advances upwardly following the load as the load is supported by the other thereof, the load being rocked into alternate co-operation with the fulcrums, said fulcrum-forming means being supported against downward movement when a downwardly acting force is applied by the co-operating load.

Another object of this invention is to provide means of the above character in which each fulcrum is connected in co-operative relation to respective fulcrum-anchoring means slidable along guide means to move the fulcrum upwardly when the load is raised, and to securely grip the guide means when downwardly directed forces are applied to the fulcrum, the guide means being secured against longitudinal movement, but at least one of the guide means engaged by each fulcrum anchoring means being rotatable angularly about its axis whereby the rotation of the rotatable guide means, while a directed force is facing upon the respective fulcrums, will produce controlled downward movement of the fulcrum.

Another object of this invention is to provide a plurality of parallel guides, at least one of said guides being cylindrical and rotatable about its axis, a plurality of fulcrum anchoring means each comprising a runner adapted to be connected to a load engaging fulcrum, the runner being adapted to slide freely along and in co-operation with a pair of said parallel guides, at least one of which is rotatable, a trailer adapted for sliding longitudinally of the said pair of guides, the trailer being gravitationally urged downwardly away from the runner, a pair of apertured dog or lock levers each encircling a portion of a respective one of said guides, the first lock lever being adapted to co-operate with a fulcrum-forming portion of said runner adjacent one of its ends, and being pivotally connected to a link adjacent its other end, the second lock lever being pivotally connected to said link at a point spaced from said first lever and adjacent its other end being in co-operative relation to a fulcrum-forming portion of the trailer, whereby movement of the runner away from the trailer serves to lock the levers in relation to the respective guides to effect frictional interlocking of said levers and guides to secure the runner in fixed corresponding relation to the guides, and whereby relative movement of the runner toward the trailer tends to swing the levers into non-locking relationship relative to the guides.

A further object of this invention is to provide a device of the above character in which at least one of the

guides is right cylindrical, secured against axial displacement and journaled for angular rotation about its axis, whereby rotation of said guide when the lock levers are in locking engagement with said guides permits controlled movement of the fulcrum anchoring means longitudinally of the guide in the same direction which normally results in firm locking of the anchoring means in fixed relation to the guides in the absence of such rotation.

10 The above and other features and objects of the invention will in part be obvious and will in part be apparent to those having ordinary skill in the art to which this invention pertains from the accompanying description and drawings.

15 In the drawings:

Fig. 1 is a view in perspective of a device embodying the present invention in what presently appears to be a preferred form in co-operative engagement with an elongate metal bar;

20 Fig. 2 is a fragmentary view in rear elevation of a portion of the device shown in Fig. 1, showing fulcrum anchoring means in association with a pair of guide members;

25 Fig. 3 is a view in side elevation of the structure illustrated in Fig. 2 taken along the line 3—3 in Fig. 2;

Fig. 4 is a view in vertical section taken along the line 4—4 in Fig. 3, the fulcrum anchoring means being shown in locked relationship to the guides;

30 Fig. 5 is a view in elevation, partly in section, of the mechanism illustrated in Fig. 4, the anchoring means being in unlocked relationship to the guides;

35 Fig. 6 is a schematic view in front elevation of a device of the character illustrated in Fig. 1 in co-operative relation to an elongate metal bar to be lifted, illustrating movement of the bar and accompanying movement of the fulcrums and anchoring means therefor;

Fig. 7 is a view similar to Fig. 6 in which the metal bar has been raised to a position higher than that in which it is shown in Fig. 6;

40 Fig. 8 is a view in front elevation of the device shown in Figs. 6 and 7 in association with a metal bar illustrating operation of the device incident to lowering of the bar;

45 Fig. 9 is a view in horizontal section taken along the lines 9—9 in Fig. 6, portions of the device shown in Fig. 6 being omitted; and

Fig. 10 is a view in vertical section of a modified form of embodiment of the invention generally corresponding to Fig. 4.

50 In the specification and the drawings, like reference characters indicate like parts.

The device illustrated in Fig. 1 has a strong, rigid base 20 of substantially rectangular shape supported upon swivel casters 21. A pair of spaced, parallel, upright, 55 side frame members 22, 23 of substantially triangular shape are secured in unitary relation to base 20 adjacent their lower or base edges. A top spreader member 24 is supported by, extends between and couples the upper portions of spaced side frame members 22, 23 to which it is secured in fixed relation. An upright web 25 extends substantially perpendicularly to base 20 and side frame members 22, 23. Web 25 adjacent its lower edge is secured to base 20 and along its upright lateral edges to the side frame members 22, 23 to strengthen and rigidify the assembly, which comprises base 20, side frame members 22, 23, top spreader member 24 and web 25, and which serves as the frame of the device illustrated in Fig. 1.

It may be noted that the side frame members 22, 23 illustrated in Fig. 1 are substantially right triangular in shape. Each of the side frame members 22, 23 has a vertical edge 36 and an inclined edge 37 which extend

from adjacent base 20 upwardly toward top spreader member 24. A corresponding triangular portion of each of the side frame members 22, 23 is cut away to provide a notch in the inclined edge 37, each of the notches being bounded by a supporting or lower edge face 38 and a second edge face 39 which may be substantially parallel to the respective edge 36.

Four spaced, parallel guide members 26, 27, 28 and 29 extend between and are supported in co-operative relationship with base 20 and top spreader member 24. Guide members 26 and 27, as shown, are cylindrical bars the end portions of which are secured in fixed relation to base 20, and top spreader member 24, respectively. I prefer that guide members 26 and 27 be secured to base 20 by any suitable means which will preclude axial displacement of those members relative to base 20. Guide members 28 and 29 have their lower end portions journaled for rotation in base portion 20 and are secured against axial displacement relative to the base portion 20 by collars or any suitable means (not shown). Guide members 28 and 29 extend upwardly from base 20 through spreader member 24 in spaced, parallel relation to each other and to stationary guides 26 and 27. In the device shown in Fig. 1, suitable aligned bearing members, such as bronze bearing sleeves 32 and 33 may be provided respectively in base 20 and top spreader member 24 for co-operatively supporting the guides 28 and 29 which are thus journaled for axial rotation, while, as previously explained, being secured against axial displacement.

Guide members 28 and 29, as shown in Fig. 1, project upwardly through top spreader member 24. Levers 30, 31 are secured, respectively, to the projecting portions of guides 28 and 29, and extend radially therefrom. I prefer that levers 30 and 31 be connected so as to remain in substantially parallel relationship to each other. This may be accomplished by means of a suitable coupling or link member, and, as shown in Fig. 1, the link may be in the form of an elongate handle 35 through which a pair of parallel, longitudinal bores 34 extend. Levers 30 and 31 are received in respective bores 34. The bores 34 may be larger in diameter than the levers 30, 31 so as to loosely receive the respective levers. Coupling handle 35 may be secured to lever 30 in a manner which precludes axial movement of handle 35 along lever 39 while permitting axial and canting movement of lever 31 in the respective bore 34 provided in handle 35. Thus, guide 28 may be oscillated about its axis by swinging of lever 30 and associated coupling handle 35. Coupling handle 35 in co-operative relation with lever 31 serves to effect a corresponding movement of lever 31 to oscillate guide member 29. The coupling handle 35, determines the maximum and minimum spacing between levers 30 and 31, and serves to limit swinging of those levers to a predetermined arc.

I provide anchoring means designated generally by reference characters 50 and 51 in Figs. 6, 7, and 8 each in co-operating relation with a respective pair of guides 26, 28, 29, 27. That is, I provide one anchoring means 50 in co-operating relation with stationary guide 26 and oscillatable guide 28, and a second anchoring means 51 in co-operative association with oscillatable guide 29 and stationary guide 27. Each of the anchoring means has a runner 41 upon which an external hook 42 is secured. Connecting means such as chains 43, 46, are each secured to a respective hook 42. Each chain 43, 46 extends in substantially spaced parallel relation upwardly over the top spreader member 24 and therefrom downwardly to an object to be lifted, or supported, such as bar 44. An end hook 45, 47 is provided respectively on each chain 43, 46 adjacent the load, bar 44, supported thereby. Hooks 45, 47, respectively engage links of chains 43, 46 spaced from the hook end of the chain to form respective loops 48, 49 of fixed size encircling and which serve as supporting and fulcrum means for the load, bar 44.

The anchoring means 50, 51 both function alike and are constructed alike, except that one may be a mirror image of the other as shown in Fig. 1. For this reason the detailed description of anchor 50 which follows is equally applicable to anchor 51. Like reference characters will be applied to corresponding parts of the anchors 50 and 51.

Anchor 50 is illustrated in detail in Figs. 2, 3, 4, and 5. Runner 41 (as shown most clearly in Figs. 1 and 3) may be a tube-like member of rectangular section having a top portion 52 and a bottom portion 53 in spaced parallel relation. An aperture 54 is provided in top portion 52 through which guide 28 co-operatively extends. Aligned apertures 55 and 56 are provided in portions 52 and 53, respectively, through which guide 26 co-operatively extends. The co-operation of runner 41 and guides 26 and 28 serves to limit runner 41 to movements longitudinally of the guides. The apertures 54, 55, and 56 are of a size and shape which allows smooth, free sliding of runner 41 along the guides 26, 28 with a minimum of play.

A trailer 57 is mounted for reciprocation along guides 26, 28 below runner 41. As shown most clearly in Figs. 4 and 5, trailer 57 has a top portion 58 and bottom portion 59 joined in parallel relation by web or wall 60. A pair of aligned apertures 61, 62 are provided respectively in top and bottom portions 58, 59 of trailer 57. A third aperture 63 is provided in bottom portion 59 of trailer 57 in spaced, parallel relationship to the aligned apertures 61, 62. Guide 28 extends through aligned apertures 61, 62 while guide 26 extends through aperture 63. The apertures 61, 62, 63 are each of a size and shape which allows smooth, free sliding of trailer 57 along the guides 26, 28 with a minimum of play. The co-operation of trailer 57 and guides 26, 28 is such that the trailer is substantially limited to movements longitudinally of the guides. As shown most clearly in Figs. 2, 4, and 5, runner 41 and trailer 57, when in co-operative engagement with guides 26, 28 do not directly engage each other.

As shown in Figs. 1, 2, 4 and 5, an aperture is provided in web or wall 60 of trailer 57 adjacent bottom portion 59 of the trailer. This aperture, indicated by reference character 64, in the illustrated embodiment is a rectangular opening, the lower bounding face portion of which is shown coplanar with the upper surface of bottom portion 59. The face portion bounding aperture 64 opposite the bounding face portion which is coplanar with the upper surface of trailer bottom 59 is designated by the reference character 64a and serves as a fulcrum in the manner which will be explained subsequently herein.

A pair of levers 65 and 66 are provided. Long or trailer lever 65 and short or runner lever 66 are both longitudinally slotted from their corresponding respective ends 67, 68 to form a pair of spaced, parallel integral arm portions on each lever. Respective end portions of a connecting link 69 extend into the slots between the arm portions adjacent ends 67, 68 of the levers. Link 69 is joined to and between the arm portions of lever 65 by pivot pin 70 and to and between the arm portions of lever 66 by pivot pin 71. A fulcrum parallel to pivot pin 71, such as bar 72, is a fixed or integral portion of runner 41 adapted to co-operate with lever 66 adjacent its end 73 remote from its end 68. An aperture 74 is provided in lever 66 between and spaced from pivot pin 71 and fulcrum bar 72. Guide 26 extends through aperture 74, which, as a result, is substantially in registry with apertures 55 and 56 in runner 41. The slot between the integral arm portions of lever 65 is longer than the slot provided in lever 66. Guide 26 extends through the slot between the arm portions of lever 65 and may co-operate with lever 65 only to the extent of assisting in the alignment of the lever in conjunction with guide 28 which extends through an aper-

ture 75 provided in lever 65 adjacent end 76 thereof. Lever 65 adjacent its end 76 has a portion which extends into aperture 64 provided in a web or wall 60 of trailer 57. As shown in Fig. 5, aperture 64 is so located that lever 65 may lie in flatwise engagement with the upper surface of portion 59 of runner 57 and also in flatwise engagement with the under face of lower portion 53 of runner 41. As shown in Fig. 5, the link 69 is of a length such that it and the fulcrum 72 support lever 66 in substantially parallel relation to lever 65 when the latter is between and in flatwise engagement with the opposed faces of bottom portions 59 and 53 of trailer 57, and runner 41, respectively. Thus, when runner 41, trailer 57, levers 65, 66 and link 69 are in the relative positions illustrated in Fig. 5, the anchoring means is freely slideable longitudinally of the guides 26, 28. When guides 26, 28 as illustrated in Fig. 1, are in upright position, the anchoring means tend to be urged downwardly by the force of gravity. However, downward movement of runner 41, as shown in Fig. 1, is subjected to restraining influences imposed upon hook 42 through chain 43 by the load, bar 44. The load, bar 44, tends to draw chain 43 in a direction such that the hook 42 is urged upwardly by forces exceeding the force of gravity. Trailer 57 is not directly connected to runner 41 and tends to move downwardly under force of gravity (represented by the arrow G, Fig. 4) at all times. The load, bar 44, through chain 43 and hook 42, serves to impose an upwardly directed force, represented by the arrow L (Fig. 4), upon runner 41. The force L is greater than the force of gravity G acting upon runner 41. Thus, the forces G and L serve to urge the runner 41 and trailer 57 in opposite directions. Such movement of the runner and the trailer serves to move the levers 65, 66, into non-parallel relation in the plane in which Fig. 4 is taken, that is, as trailer 41 is moved in the direction of arrow L, fulcrum 72 in mechanical engagement with lever 66 adjacent its end 73, tends to raise that end of lever 66. Likewise, movement of trailer 57 in the direction indicated by arrow G results in co-operative engagement between the upper face of lever 65 and the edge face bounding aperture 64. Thus, as viewed in Fig. 4, lever 65 is urged to swing in a clockwise direction about pivot pin 70 while lever 66 is urged to move in the opposite or counter-clockwise direction about pivot pin 71. Swinging of levers 65 and 66 in opposite directions from the positions of parallelism as shown in Fig. 5 to the positions of non-parallel relationship, shown in Fig. 4, results in gripping or binding engagement between the wall of aperture 74 and the surface of guide 26 and the wall of aperture 75 and the surface of guide 28. The greater the force exerted in the direction L upon runner 44, the greater the gripping of levers 65, 66 upon guides 28, 26 will be. Thus the greater the load supported by chains 43, 46 the greater the resistance of the anchoring means to movement in the direction indicated by arrow L.

As shown in Fig. 1, an object to be lifted, such as bar 44, is supported by two spaced, encircling fixed loop portions of chains 43, 46. To place the chains in encircling relation to the load, such as bar 44, one end of bar 44 is raised by suitable means such as a jack or the like which applies the supporting force indicated by arrow J to permit positioning of the chains. As shown in Fig. 6, chains 43, 46 extend from the loop portions encircling bar 44 to hook 42 of the respective anchoring means 50, 51, when the latter are positioned adjacent the upper ends of the guide members along which they travel.

The bar 44, at the outset, may be in the position illustrated in full lines in Fig. 6. The anchoring means 50, 51 as previously explained, move freely downwardly under gravity, but resist movement upwardly along the guides. The weight of the runner 41 of each anchoring means 50, 51 is sufficiently great to take up the slack in the respective chains 43, 46 extending to the bar 44. With bar 44 in the starting position just described, the

center of gravity C of bar 44 lies between the spaced locations supportingly engaged by chains 43, 46. The support J may be withdrawn from the elevated end of the bar and the bar will remain in the position shown in full lines, supported by chains 43, 46. To raise bar 44 from the position shown in full lines in Fig. 6, it is swung clockwise through an angle indicated by arrows O to the position shown in dashed lines in Fig. 6, chain 43 providing the fulcrum at 77 about which the bar swings. The load is thus placed upon chain 43 and is removed from chain 46 by swinging through angle O. Chain 46, when relieved from the load of bar 44, tends to slacken, but anchor 51 slides down guides 27, 29 and takes up such slack. Thereafter, bar 44 may be swung in a counter-clockwise direction, through an angle as indicated by arrows T, about a fulcrum point at 78 provided by chain 46. While bar 44 swings as indicated by arrows T, anchor 50 slides down guides 26, 28 taking up slack in chain 43 as the chain moves into position to serve as a fulcrum at 79. The next swing of bar 44 would be about the fulcrum point 79 provided by chain 43. Bar 44 is thus raised from the position shown in full lines to that shown in dot-dash lines by swinging successively through angles O and T.

The weight of bar 44, when swinging about a fulcrum point provided by chain 43 or 46, is always nearly in balance and the effort required to swing bar 44 is small. The bar 44 is thus easily oscillated, alternately in a clockwise direction, supported by chain 43, and in a counter-clockwise direction, supported by chain 46, as shown in Fig. 6. Continuous repetitive oscillation of bar 44 in the teeter-totter-like manner in co-operative relation with the two alternately advancing fulcrums, as described above, will effect raising of bar 44 to the elevation desired.

Normal functioning of anchoring means 50, 51 is such that movement of runner 41 relative to trailer 57 is very slight, nearly imperceptible. The small degree of relative movement is believed to stem from the fact that the angular positions of the levers relative to the guides is altered by a small angle in shifting between the gripping and non-gripping positions.

It may be noted that as the chain 43 or 46 tends to slacken, runner 41 tends to slide down the guides and fulcrum 72 tends to drop from contact with lever 66. However, end 73 of lever 66 tends to swing downward toward a horizontal position in which the lever is perpendicular to guide 26. In so moving, lever 66 normally rests upon fulcrum 72. Link 69 also tends to fall as does lever 65 toward the relative positions shown in Fig. 5 which are limit positions of full release. It may be noted that if lever 65 or 66 sticks, the runner 41 will fall against lever 65 and jar the levers to release them. Trailer 57 of course tends to slide down the guides away from runner 41 and thus keeps the levers in ready-to-grip relation to the guides in order that slight upward movement of runner 41 will effect firm engagement between the levers and guides to preclude further upward movement of the anchoring means.

When a load, such as bar 44, is to be transported upon the device illustrated in the drawings, I prefer that it rest on the surfaces 38 which are inclined downwardly from edge face 37 to surface 39, and against surfaces 39 of the frame members 22, 23. Chains 43, 46 are left in co-operative relation to bar 44 for safety and convenience.

Bar 44 may be lowered easily by swinging handle 35 back and forth through an arc as indicated by arrow H in Fig. 8. Such oscillatory movement of handle 35 effects unison corresponding oscillation of guides 28, 29 about their respective axes, the arc of swing of handle 35 being limited by co-operation of handle 35 with levers 30, 31, all as previously explained. Movement of handle 35 and accompanying oscillatory rotation of guides 28, 29 permit controlled sliding movement of anchoring means 50, 51 longitudinally of the respective guides. The speed and distance of movement of the anchoring means ap-

pear to be related to the frequency of oscillation and magnitude of the force applied through chains 43, 46 to respective hooks 42 and tending to urge the respective anchoring means 50, 51 toward top spreader member 24.

I have found that the anchoring means may be modified as shown in Fig. 10. The anchoring means illustrated in Fig. 9 differs from the structure of those described above in that aperture 74a in lever 66a and aperture 75a in lever 65a are elongated longitudinally of the respective levers to each respectively receive a pair of co-operating shoes 90, 91, as well as a respective guide 28, 29. The shoes 90 are positioned in opposition in co-operative relation with opposite sides of guide 26a, and with lever 66a. Shoes 91 are in similar co-operative relation with guide 28a and lever 65a. The shoes 90, 91 move longitudinally of guides 26a 28a in co-operative association with levers 66a, 65a. As previously explained, the guides are primarily loaded in tension and the provision of shoes 90, 91 contributes to the useful life of the guides by protecting their surfaces from permanent surface distortion through distribution of gripping forces over a greater area. A lip 59a may be provided on trailer 57 to permit lever 65a to move into parallel relation to the bottom portion 59.

Having thus described the invention it will be apparent to those having ordinary skill in the art to which this invention pertains, that various changes may be made in the disclosed embodiment, without departing from either the spirit or the scope of the invention.

Therefore, what is claimed as new and desired to be secured by Letters Patent is:

1. In combination with a pair of parallel guides, an anchoring means adapted for co-operation with said pair of parallel guides, said anchoring means comprising a runner slideable along the guides, a trailer slideable along the guides, said runner having a fulcrum adjacent but spaced from one of said guides, said trailer having a fulcrum adjacent but spaced from the other of said guides, a pair of levers each co-operating with a respective one of said fulcrums and the guide adjacent thereto, and a link coupling the ends of the levers whereby the levers grip the guides while the runner and the trailer are urged apart.

2. In combination with a pair of parallel guides, an anchoring means adapted for co-operation with said pair of parallel guides, said anchoring means comprising a runner slideable along the guides, a trailer slideable along the guides, said runner having a fulcrum adjacent but spaced from one of said guides, said trailer having a fulcrum adjacent but spaced from the other of said guides, a pair of gripping shoes in co-operating relation with each of said guides, a pair of levers each co-operating with a respective one of said fulcrums and one pair of said guide gripping shoes adjacent thereto, a link coupling the ends of the levers whereby the levers urge the shoes into gripping relation with the guides while the runner and trailer are urged apart.

3. A lifting, supporting and lowering device comprising a frame, a plurality of parallel upwardly extending guides secured to said frame, a plurality of anchoring means each co-operating with two guides one of which is oscillatable, each of said anchoring means comprising a runner slideable along the guides, a trailer slideable along the guides, said runner having a fulcrum adjacent but spaced from one of said guides, said trailer having a fulcrum adjacent but spaced from the other of said guides, a pair of levers each co-operating with a respective one of said fulcrums and the guide adjacent thereto, a pair of substantially parallel means each coupling a respective one of said runners to a portion of a load in spaced relation to the center of gravity thereof disposed between said means, the load through said means tending to urge the runner toward one end of the guides while the trailer portion of said anchoring means is gravitationally urged away from said runner whereby swinging of the load in teeter-totter fashion permits alternate anchoring and

movement of the anchoring means, only one thereof moving at any time during raising of the load and whereby both anchoring means may be advanced along the guides in unison under forces applied by the load when the oscillatable guide is oscillated to lower the load.

4. In combination with a pair of parallel guides, an anchoring means adapted to co-operate with said pair of parallel guides one of which is oscillatable, said anchoring means comprising a runner slideable along and adapted to co-operatively engage two spaced portions of a first one of said guides and one portion of the second of said guides, a fulcrum on said runner adjacent but spaced from said first guide and between said guides, a first lever adapted to co-operate with said fulcrum and a portion of said adjacent guide intermediate said runner engaged portions, a link connected to the end of said lever remote from said fulcrum, a trailer slideable along said guides and adapted to co-operatively engage two spaced portions of the second guide and one portion of the first guide, said trailer having a fulcrum adjacent said second guide and remote from said first guide, a second lever in co-operative engagement with said trailer fulcrum and adapted to co-operate with a portion of said second guide intermediate said trailer engaged portions, said second lever adjacent its end remote from the trailer fulcrum being connected to said link in spaced relation to said first lever, whereby relative movement of the trailer away from the runner tends to move the levers into firm gripping engagement with the stationary guides to preclude movement of the runner in the opposite direction, and whereby oscillation of the oscillatable guide allows controlled movement of the anchoring means in said opposite direction when appropriate force is applied to the runner tending to move it in that direction.

5. In combination with a pair of parallel guides, an anchoring means adapted to co-operate with said pair of parallel guides one of which is oscillatable, said anchoring means comprising a runner slideable along and adapted to co-operatively engage two spaced portions of a first one of said guides and one portion of the second of said guides, a pair of shoes adapted to co-operate with said first guide intermediate said two spaced portions of the first guide engaged by the runner, a fulcrum on said runner between said guides and adjacent but spaced from said first guide and shoes, a first lever adapted to co-operate with said fulcrum and said shoes, a link connected to the end of said lever remote from said fulcrum, a trailer slideable along said guides and adapted to co-operatively engage two spaced portions of the second guide and one portion of the first guide, a pair of shoes adapted to co-operate with said second guide intermediate said two spaced portions of the second guide engaged by said trailer, said trailer having a fulcrum adjacent said second guide and remote from said first guide, a second lever in co-operative engagement with said trailer fulcrum and adapted to co-operate with the pair of shoes adapted to co-operate with said second guide intermediate said trailer engaged portions, said second lever adjacent its end remote from the trailer fulcrum being connected to said link in spaced relation to said first lever, whereby relative movement of the trailer away from the runner tends to actuate the levers to effect firm gripping engagement of the shoes with the stationary guides to preclude movement of the runner in the opposite direction, and whereby oscillation of the oscillatable guide allows controlled movement of the anchoring means in said opposite direction when appropriate force is applied to the runner tending to move it in that direction.

6. A lifting, supporting and lowering device comprising a base, a pair of parallel upright side members, a top spreader member extending between, joining and supported by said side members, a plurality of guide members supported in parallel relation by said base and top spreader member and secured against longitudinal displacement relative to the base, one guide member being

mounted for oscillatory angular movement, means for oscillating said oscillatable guide member, two anchoring means, each anchoring means in co-operating relation to two guide members one of which is oscillatable, each anchoring means comprising a runner slideable along and adapted to co-operatively engage two spaced portions of a first one of said guides and one portion of the second of said guides, a fulcrum on said runner between said guides adjacent but spaced from said first guide, a first lever adapted to co-operate with said fulcrum and a portion of said adjacent guide intermediate said runner engaged portions, a link connected to the end of said lever remote from said fulcrum, a trailer slideable along said guides and adapted to co-operatively engage two spaced portions of the second guide and one portion of the first guide, said trailer having a fulcrum adjacent said second guide and remote from said first guide, a second lever in co-operative engagement with said trailer fulcrum and adapted to co-operate with a portion of said second guide intermediate said trailer engaged portions, said second lever adjacent its end remote from the trailer fulcrum being connected to said link in spaced relation to said first lever, a pair of elongate members each coupled to a respective anchoring means and to a load, said elongate members being adapted to extend in substantially parallel relation from the anchoring means over the top spreader member to the load, each of said elongate members being adapted to co-operatively support a load with its center of gravity disposed between the elongate members whereby the load may be raised by rocking it in teeter-totter fashion and lowered by oscillation of the oscillable guide.

7. A lifting, supporting and lowering device comprising a base, a pair of parallel upright side members each having one of a pair of parallel inclined edge faces adapted to guide an object incident to alteration of its elevation and an object supporting face adjacent each inclined edge face for supporting an object as when transporting same, a top spreader member extending between, joining and supported by said side members, a plurality of guide members supported in parallel relation by said base and top spreader member and secured against longitudinal displacement relative to the base, one guide member being mounted for angular oscillatory movement, means for oscillating said oscillatable guide member, a plurality of anchoring means, each anchoring means in co-operating relation to said oscillatable guide member and one other of said guide members, each anchoring means being biased toward unidirectional movement longitudinally of the respective guides and adapted to engage said guides to preclude opposite movement longitudinally of the guides so long as neither of the guides oscillates in an angular fashion, a pair of elongate members each coupled to a respective anchoring means and to an object to be supported, said elongate members extending in substantially parallel relation over the top spreader member between the anchoring means and said object, each of said elongate members being adapted to co-operatively support an object with its center of gravity disposed between the elongate members whereby the object may be raised by rocking it in teeter-totter fashion and lowered by oscillation of the oscillatable guide.

8. A lifting, supporting, transporting and lowering device comprising a base having a plurality of supporting traction wheels, a pair of parallel upright side members, each having one of a pair of parallel inclined edge faces adapted to guide an object incident to alteration of its elevation, an object incident to alteration of its elevation, an object supporting face adjacent each inclined edge face for supporting an object as when transporting same, a top spreader member extending between, joining and supported by said side members, a plurality of guide members supported in parallel relation by said base and top spreader member and secured against longitudinal displacement relative to the base, one guide member being

mounted for oscillatory angular movement, means for oscillating said oscillatable guide member, two anchoring means, each anchoring means in co-operating relation to said oscillatable guide member and one other of said guide members, each anchoring means comprising a runner slideable along and adapted to co-operatively engage two spaced portions of a first one of said guides and one portion of a second one of said guides, a fulcrum on said runner between said guides, said fulcrum being adjacent but spaced from said first mentioned guide, a first lever adapted to co-operate with said runner fulcrum and a portion of said adjacent guide intermediate said runner engaged portions, a link connected to the end of said lever remote from said fulcrum, a trailer slideable along said guides and adapted to co-operatively engage two spaced portions of the second guide and one portion of the first guide, said trailer having a fulcrum adjacent said second guide and remote from said first guide, a second lever in co-operative engagement with said trailer fulcrum and adapted to co-operate with a portion of said second guide intermediate said trailer engaged portions, said second lever adjacent its end remote from the trailer fulcrum being connected to said link in spaced relation to said first lever, a pair of elongate members each coupled to a respective anchoring means and to a load, said elongate members being adapted to extend in substantially parallel relation from the anchoring means over the top spreader member to the load, each of said elongate members being adapted to co-operatively support a load with its center of gravity disposed between the elongate members whereby the load may be raised by rocking it in teeter-totter fashion and lowered by oscillation of the oscillatable guide.

9. A lifting, supporting and lowering device comprising a base, a pair of parallel upright side members each having one of a pair of parallel inclined edge faces adapted to guide an object incident to alteration of its elevation and an object supporting face adjacent each inclined edge face for supporting an object as when transporting same, a top spreader member extending between, joining and supported by said side members, a plurality of guide members supported in parallel relation by said base and top spreader member and secured against longitudinal displacement relative to the base, a plurality of said guide members being mounted for angular oscillatory movement, means for oscillating said oscillatable guide members in unison, a plurality of anchoring means, each anchoring means in co-operating relation to one of said oscillatable guide members and one other of said guide members, each anchoring means being biased toward unidirectional movement longitudinally of the respective guides and adapted to engage said guides to preclude opposite movement longitudinally of the guides so long as neither of the guides oscillates in an angular fashion, a pair of elongate members each coupled to a respective anchoring means and to an object to be supported, said elongate members extending over the top spreader member between the anchoring means and said object, each of said elongate members being adapted to co-operatively support said object with its center of gravity disposed between the elongate members, whereby the object may be raised by rocking it in teeter-totter fashion and lowered by unison oscillation of the oscillatable guides.

10. A lifting, supporting, transporting and lowering device comprising a base having a plurality of supporting traction wheels, a pair of parallel upright side members, each having one of a pair of parallel inclined edge faces adapted to guide an object incident to alteration of its elevation, an object supporting face adjacent each inclined edge face for supporting an object as when transporting same, a top spreader member extending between, joining and supported by said side members, a plurality of guide members supported in parallel relation by said base and top spreader member and secured against longitudinal

displacement relative to the base, a plurality of said guide members being mounted for oscillatory angular movement, means for oscillating said oscillatable guide members in unison, a plurality of anchoring means, each anchoring means in co-operating relation to one of said oscillatable guide member and one other of said guide members, each anchoring means comprising a runner slideable along and adapted to co-operatively engage two spaced portions of a first one of said guides and one portion of a second of said guides, a fulcrum on said runner between said guides, said fulcrum being adjacent but spaced from said first guide, a first lever adapted to co-operate with said runner fulcrum and a portion of said adjacent guide intermediate said runner engaging portions, a link connected to the end of said lever remote from said fulcrum, a trailer slideable along said guides and adapted to co-operatively engage two spaced portions of the second guide and one portion of the first guide, said trailer having a fulcrum adjacent said second guide and remote from said first guide, a second lever in co-operative engagement with said trailer fulcrum and adapted to co-operate with a portion of said second guide inter-
